UNITED STATES PATENT OFFICE.

CHARLES E. JONES, OF CHICAGO, ILLINOIS, ASSIGNOR TO METAL ARTS & CRAFTS CO.,
OF CHICAGO, ILLINOIS, A CORPORATION OF ILLINOIS.

DESIGN FOR AN ELECTRIC-CANDLE-BASE HICKEY.

47,924.

Specification for Design.

Patented Oct. 5, 1915.

Application filed June 1, 1915. Serial No. 31,588. Term of patent 3½ years.

To all whom it may concern:

Be it known that I, CHARLES E. JONES, a citizen of the United States, residing at Chicago, in the county of Cook and State of Illinois, have invented a certain new, original, and ornamental Design for an Electric-Candle-Base Hickey, of which the following is a specification, reference being had to the accompanying drawing, forming part thereof.

The figure is a front elevation of an electric candle base hickey, showing my new design.

I claim:

The ornamental design for an electric candle base hickey, as shown.

CHARLES E. JONES.
